UNITED STATES PATENT OFFICE.

ERICH JOHNSON, OF CLEVELAND, OHIO.

RAZOR-BLADE HOLDER.

1,324,968.

Specification of Letters Patent. Patented Dec. 16, 1919.

Application filed June 23, 1919. Serial No. 306,106.

To all whom it may concern:

Be it known that I, ERICH JOHNSON, a citizen of the United States, residing at Cleveland, in the county of Cuyahoga and 5 State of Ohio, have invented certain new and useful Improvements in Razor-Blade Holders, of which the following is a specification.

This invention relates to a device which 10 is designed primarily for use in connection with blades for safety razors, it has for its principal object the provision of means whereby all types of safety razor blades may be securely held while stropping the same, 15 the means provided being so constructed as to permit being held in the hand in much the same manner as that when stropping the old types of razors.

Further and more limited objects of the 20 invention are the provision of means which will permit inserting the blades between the clamping members in a simple and efficient manner, the provision of a device which may be cheap of manufacture, durable, attractive in appearance and one which will occupy a minimum amount of space thereby permitting the same to be conveniently carried.

The foregoing may be accomplished in the 25 embodiment of my invention illustrated in the accompanying drawing, wherein like reference numerals designate similar parts throughout the various views, and in which Figure 1 is a central longitudinal section 30 thereof; Fig. 2 is a sectional plan; Fig. 3 is a longitudinal section similar to Fig. 1, but showing the manner in which the blade is inserted, the blade being indicated in dotted lines; Fig. 4 is a detail perspective of the 35 ends of the blade clamps and Figs. 5, 6, 7, and 8 are detail views of modified forms of 40 clamp retaining means.

In Figs. 1 to 3 wherein is shown the preferred embodiment of my invention, 1 represents the handle which may be of metal, 45 hard rubber or the like, and which is provided with a central bore 2 into which is placed the stem 3 of one of the members of a clamp indicated as a whole at 4. At the 50 end of the handle remote from the clamping member 4 the bore 2 is enlarged to accommodate a coil spring 5, said spring being interposed between the bottom of the bore 2 and a washer 6 secured to the end of the

stem 3 in any convenient manner, in the 55 drawing shown as being riveted thereto. At the opposite end the handle is provided with a recess 7 which is substantially rectangular in cross section and into which are retained the ends 8 and 9 of the blade 60 clamps 10 and 11 respectively. The clamp 11 is formed integral with the stem 3, the clamp 10 being a separate unit. These 65 clamps are substantially identical in shape, both being provided with lateral flanges 12 between which are clamped the razor blades, and with convex extensions 13 for the purpose of allowing that type of razor blade which is formed with a thickened upper edge such as the blade known to the trade 70 as the "Ever Ready." At the end of the member 11 the flange 12 is bent at right angles to itself for a short distance thereof, and then rearwardly upon itself thereby forming a clip 14 within which is placed 75 the end of the portion 12 of the clamp 10, and formed upon the end of the convex portion 13 of the clamp 10 is a similar shaped clip 15 which engages a corresponding portion of the clamp 11.

In operation the device is grasped with the clamp in the left hand and with the handle in the right hand, the clamps are drawn against the tension of the spring 5 until the portions 8 and 9 of the clamps are 85 freed from the recess 7, and with the thumb of the operator the clamp 10 is swung using the junction of the clips 14 and 15 as a pivot. The razor blade is then inserted therebetween and the clamps allowed to 90 recede until the portions 8 and 9 are within the recess 7, this being accomplished by the action of the spring 5, and the device is then ready to be used in identically the same manner as that which is experienced 95 when using the old type of razor.

In Figs. 5, 6, 7, and 8 I have shown various modifications of the means for retaining the clamps in position, all of which comprises a spring actuated means with the exception of the one shown in Fig. 5, this being provided with a knurled nut 18 threaded upon the end of the stem 3 and while I have shown these particular forms of device it is obvious that numerous other ways will 100 suggest themselves to those familiar with the art and I do not wish to limit myself further than is required by the same and 105

that which is within the scope of the appended claim.

I claim:

5 A razor blade holder comprising a handle having a recess, and a pair of clamping members the inner ends of which are movable into and out of said recess and the outer end of each of which has a hooked clip pre-

sented inwardly and adapted to engage part of the outer end of the other member.

10 In testimony whereof I do affix my signature in presence of two witnesses.

ERICH JOHNSON.

Witnesses:

JOHN A. BOMMHARDT,
ROBERT L. BRUCK.
